UNITED STATES PATENT OFFICE.

GEORGE D. WOODWORTH, OF BROOKLYN, NEW YORK.

MACHINE FOR STAMPING OR BRANDING CIGARS.

SPECIFICATION forming part of Letters Patent No. 466,480, dated January 5, 1892.

Application filed March 6, 1891. Serial No. 383,986. (No model.)

To all whom it may concern:

Be it known that I, GEORGE D. WOODWORTH, of Brooklyn, in the county of Kings and State of New York, have invented certain new and useful Improvements in Machines for Stamping or Branding Cigars, of which the following is a specification, reference being had to the accompanying drawings.

10 The present invention relates to a new and novel mechanism by which cigars may be rapidly impressed on their wrappers or outer surfaces with letters or other characters.

The invention consists, essentially, of a receiver or feed-box made capable of adjustment to various lengths and sizes of cigars, a die or impression plate, and an impression mechanism by which the cigars are singly taken from the feed-box, pressed to contact 20 with the die, and dropped out of or fed from the machine.

I will first describe my improved mechanism, and in the claims to follow the description will point out the elements and combination of elements I consider as new and as of 25 my invention.

Figure 1 of the drawings shows a machine embodying my invention, the same being in central vertical section, the parts being in 30 their retracted position. Fig. 2 shows the die-block in perspective. Fig. 3 is a cross-section on line $x-x$ of Fig. 1, looking from the left hand of that figure. Fig. 4 is a plan view in partial section. Fig. 5 is a central 35 vertical section, the parts being in the position they have when a cigar is being forced upon the marking-die. Fig. 6 is a view of a cigar, showing letters printed or branded upon its wrapper.

40 Referring to the views in detail, 1 represents the frame and standards of the machine, 2 the base, and 3 the feed-box. The feed-box is a parallelogram in general form and has an inside width somewhat greater than the length of the longest average cigar. Its bottom 4 is inclined, as shown, slanting 45 from its rear end downwardly to the throat at its front end. To regulate the size of this throat to the thickness of the cigars being 50 branded, the inclined bottom 4 is faced with a movable metal plate 5, which is held in posi-

tion on the bottom by the thumb-screw 6, the bolt of which is attached to the plate and passes through a slot in the bottom of the box. The throat end of this plate overhangs 55 the end of the bottom of the box, and by the adjustment of the plate produces a wider or narrower opening between it and the end of the box, through which the cigars pass side-wise out of the box. 60

7 indicates the adjustable sides or partitions of the feed-box. Preferably the feed-box has fixed inclosing sides, as shown, and inner adjustable sides or partitions, though obviously the outer fixed sides or walls serve 65 mainly as supports to the partitions and the ends of the box, and so may be of a frame-like form. These fixed sides are indicated by 8.

9 represents cross-bars at the top ends of 70 the feed-box. These are slotted at 10, and through these slots pass the bolts of the thumb-screws 11, which bolts are attached to the upper edge of the partitions 9. By these means these partitions are capable of adjustment laterally in the feed-box in accordance 75 with the length of the cigars being marked, as it is between these partitions that the cigars are placed and crosswise to the box.

12 indicates strips of thin metal fastened 80 to the front end of the partitions and projecting down into the throat of the box. These are but continuations of the partitions and they measure the length of the throat-opening, as do the partitions the width of the receiving-space of the feed-box. 85

13 is the front end of the box, which at its lower end is continued by the removable thin metal plate 14. This plate, the overhang of the movable bottom 5, and the partition-strips 90 12 form the throat or opening through which the cigars are fed from the receiving-box.

The receiving or feed box is secured in proper position upon the cross-plate 15 of the standards by the bolt and nut 16. This cross-plate carries the ways 17, in which reciprocate the slide-bar 18, the stop 18^a limiting the rearward movement of the same. 95

19 is a rocking bar shaped to the general outline of cigars and centrally pivoted to the slide 100 18. The shape and attachment of this bar to the slide adapt it to conform to the shape and

position of the cigar, as it is this bar that presses the cigar to contact with the impression-die. The slide 18 is pivotally attached by the link 20 to the crank-arm 21, which is fixed to the shaft 22, on which is a hand-lever 23. A spring 24 on shaft 22 engages the arm 21 and the frame of the machine in such manner that its tension holds the parts normally in the position shown in Fig. 1, the slide 18 bearing against stop 18^a, and serves to return them to such position after the machine has been operated by depressing the hand-lever 23. An adjustable screw-stop 24^a on the frame of the machine serves to limit the movement of the lever 23 and the forward movement of the cigar-printing parts. 25 represents two bracket-arms secured to the slide 18 and projecting forward across the throat of the feed-box. It is upon these arms that the cigar to be printed or branded lies, and the cigar is held from leaving these arms by the upwardly-turned ends of the two fingers 26, which fingers are carried on the rock-shaft 27, having bearings in the frame of the machine, the fingers being held to place by the adjustable counter-weight 28, the stem of which projects from the rock-shaft, and they are prevented from rising too high by the stop-arm 28^a on shaft 28, which arm strikes against the cross-plate 15, as seen in Fig. 3.

29 are two delicate springs adjustably secured on the plate 14, and their function is to bear down on the cigar and hold it upon the arm 25 as it is moved forward out of the feed-box throat and passes over the ends of the fingers 26.

30 is the branding or impression die. It consists of a plate or sheet of metal bearing suitable characters, which plate is bent to the beveled form of the face of the die-block 31, and its longitudinal edges are sprung into the grooves 32, the plate holding in place by its elasticity. This block is secured to the front face of the heating-box 33 by dovetail connections, which afford vertical adjustment of the die-block on the heating-box. The heating-box is secured to the front frame of the machine by slots in the same and the screws 34. It is to be noted that by these 40 means the die-plate may be adjusted to print upon any portion of the length of the cigar—that is, the heating - box can be adjusted lengthwise, as well as the die-plate on its block—and the die - block can be adjusted vertically on the box. The form of die here shown is that adapted to branding cigars, 35 being a lamp or burner adapted to properly heat the die. I do not confine myself, however, to branding cigars nor to branding-dies, 45 as my machine obviously is adapted to imprint cigars when the die or character devices are of other form and adapted to give other impressions or imprints.

36 is a flap pivotally hung in the feed-box 50 against the end 13 of the box and directly over or in the throat of the same. To one of the pivots is attached the crank-arm 37, in

turn pivoted to the short arm of the lever 38, the long arm of which is linked to the operating-handle 23. It will be seen that as the 70 handle is thrown forward the lower end of the flap will be swung inwardly against the cigars that lie in the throat of the feed-box. This slightly disturbs the cigars (see Fig. 5) and prevents them becoming wedged in the throat 75 of the feed-box, so as to not feed downward and fall upon the slide and its arms 25.

The operation of the machine will now be plain. With the feed-box properly supplied and the impression-die in proper condition, 80 throwing the handle-lever forward and down against its stop forces forward the slide-bar, its platen, bracket-arms, and the cigar upon them against the retaining - fingers. This causes the forward ends of the fingers to be 85 tilted down as the cigar passes them, after which they rise behind the cigar to their first position. At the same time the motion of the parts carries the cigar under the springs 29 and against the die. The cigar is held against 90 the die long enough to insure the proper impression, when the hand-lever is returned by the operator or under the stress of the spring on its shaft. During the return motion, the fingers 26 being behind the cigar, it is pushed 95 off the arms 25, and downwardly by springs 29 upon the apron 39 or upon or to other device adapted to convey it away from the machine. During the forward motion, a cigar has fallen upon the reciprocating slide, so that as the 100 slide is returned this cigar falls off the slide and upon the carrying-arms, and the parts are in position to repeat the operation. In this way the cigars are handled very regularly and carefully yet rapidly.

105 The adjustment of the parts permits adapting the machine to any style of cigar, and its motion being lineal there is no tendency to twist or turn the cigar against the die and thereby crack or tear the wrapper.

110 What is claimed as new is—

1. The combination, in a machine for branding or impressing on cigars, of an impression-die, reciprocating mechanism arranged and operated to take the cigars singly and press 115 them upon the die, and a feed-box for feeding the cigars to the impression mechanism, substantially as set forth.

2. The combination, in a machine for impressing or branding cigars, of an impression-die, a feed-box having partitions adjustable to the length of the cigars, and reciprocating mechanism arranged and operated to take the cigars as they are fed to the same from the feed-box and press them upon the die, 125 substantially as set forth.

3. The combination, in a machine for impressing or branding cigars, of a feed-box having a delivery-opening the walls of which are adjustable to the length and thickness of the 130 cigars, an impression-die, and mechanism operating to receive the cigars from the feed-box and press them upon the die, substantially as set forth.

4. The combination of the feed-box, the reciprocating slide bearing the arms 25, the fingers 26, the springs 29, and the impression-die 30, arranged as set forth, whereby the cigars are fed singly upon said arms and carried to contact with said die and dropped from the slide.
5. The combination, with the feed-box and the impression-die, of the reciprocating slide 18, bearing the rocking bar 19 and carrying-arms 25, and the counterbalanced fingers 26, whereby the cigars are singly fed from the feed-box and to the die, substantially as set forth.
- 15 6. In combination with the feed-box and the mechanism for feeding the cigars therefrom, the heating-box 33, the die-block 31, vertically adjustable on the heating-box, and the die-plate 30, longitudinally adjustable on the said die-block, as and for the purpose set forth.
7. In combination, in the feed-box, and whereby the delivery-throat of the same is adjusted to the length and thickness of the cigars, the movable partitions 7 and the sliding bottom 5, substantially as set forth.
8. In combination with the feed-box, a flap 36, pivotally supported in the throat of the feed-box, and operative connections between the flap and the crank-arm 23, whereby the cigars lying in the throat of the feed-box are displaced and prevented wedging so as not to feed, substantially as set forth.
